UNITED STATES PATENT OFFICE.

CHARLES F. McBEE, OF ATHENS, OHIO.

SWINGING EVENER-BOARD FOR BINDING-MACHINES.

1,149,775.

Specification of Letters Patent. Patented Aug. 10, 1915.

Application filed November 4, 1912. Serial No. 729,291.

To all whom it may concern:

Be it known that I, CHARLES F. McBEE, a citizen of the United States, residing in Athens, county of Athens, and State of Ohio, have invented a new and useful Improvement in Swinging Evener-Boards for Binding-Machines, of which the following is a specification.

The object of my invention is to provide 10 a simple, convenient, and easily operated means for evening the forward ends of loose leaves in an assembly box for a binding machine, the assembly box being of the class which forms a part of the binding machine 15 and it being necessary to provide therefor a swinging evener board which may be moved out of the way when the binding is being perfected.

My invention consists of the details of 20 construction hereinafter set forth, pointed out in my claim and illustrated in the accompanying drawings in which—

Figure I shows a front elevation view of 25 my device secured to a binding machine, and Fig. II shows a perspective view of the same, the dotted lines showing the evener board opened from its hinges.

Referring to the accompanying drawings the reference numeral 10 is used to indicate 30 a binding machine provided with a base, which extends forward between the standards which are designed to support the drilling apparatus, and on one of said standards I have provided two outwardly extending 35 lugs 11 and 12, the lug 11 having an upwardly projecting stub shaft 13 and the lug 12 having a downwardly projecting stub shaft 14, said lugs being in vertical alinement. On the opposite standard of the 40 binding machine I have mounted two outwardly extending lugs 15 and 16, each being provided with an upwardly projecting stub shaft, 17 and 18 respectively, said lugs being in vertical alinement with each other 45 and spaced to receive their respective orifices in ears 19 and 20, respectively, extending outwardly from the evener board 21, when the evener board is in position to operate for that purpose. The said evener 50 board 21, is also provided on its opposite end with ears 22 and 23, in each of which is an orifice, designed to be received by the stub shafts 13 and 14 respectively by means of which the evener board is hinged to the 55 machine.

The space between the ears 22 and 23, by construction, is less than the distance from the upper surface of the lug 11 to the lower end of the stub shaft 14 and also the said space between the ears is less than the distance between the lower surface of the lug 12 and the upper end of the stub shaft 13, thus obviously providing a hinge bearing for my evener board from which the evener board may be raised and lowered, for a limited distance, but from which it cannot be removed. The position of the lugs 15 and 16 on their standard is such that when the said evener board is raised the orifices in the ears 19 and 20 will be above their respective stub shafts and when the said evener board is lowered they will be engaged, and held in place, by said stub shafts at which time, by construction of the parts, the evener board will be in proper relative 75 position to the binding machine to operate for the purpose of evening the forward ends of the papers to be bound. When the papers have been evened and perforated, the evener board is raised off of the stub shafts 17 and 18 and swung outwardly from its hinge and thus removed from the path of the binding process.

Having thus described my invention what I claim and desire to secure by Letters Patent of the United States is:

In a binding machine, the combination with vertical standards, of an evener board consisting of a rectangular body member, longitudinal face members secured to the upper and lower edges of said body members, and extending equal distances beyond the vertical edges of said body member, the extending portions being provided with bearing openings, lugs on one standard extending away from one another and engaging the projecting portions of said face members on one end of said body member so as to permit a limited vertical movement of the latter, and lugs on the opposite standard extending in the same direction to be removably engaged by the projecting portions of the face members on the opposite end of the body member.

CHARLES F. McBEE.
